JOHN S. CARROLL, OF YONKERS, N. Y., ASSIGNOR TO H. W. JOHNS-MANVILLE CO., OF NEW YORK, N. Y., A CORPORATION OF NEW YORK.

INSULATING-COVERING.

1,317,957.

Specification of Letters Patent.

Patented Oct. 7, 1919.

Application filed April 23, 1919. Serial No. 292,224.

To all whom it may concern:

Be it known that I, JOHN S. CARROLL, a citizen of the United States of America, and resident of Yonkers, in the county of Westchester and State of New York, have invented new and useful Improvements in Insulating-Coverings, of which the following is a specification.

This invention relates to waterproof sectional pipe covering of the heat-insulation type adapted for use either on bare or on otherwise covered heating or refrigerating pipes, or pipes containing hot or cold fluid, to prevent transfer of heat between the contents of the pipe and the atmosphere. The device is also adapted for use over plastic coverings, whether or not the plastic covering is made in place or applied in sections.

Principal objects of the invention are to provide a sectional covering which can be applied without loss of time and which will supplement the existing covering by the provision of a space packed with a radiation-preventing air-containing material which when installed is relatively impervious and continuous, and which is in turn covered by a waterproof exterior covering.

In the accompanying drawings illustrating a preferred form of the genus of coverings corresponding to the invention,

Figure 1 is a longitudinal section through a pipe having applied thereto a covering corresponding to the invention;

Fig. 2 is an elevation showing the inner face of one of the sections or units;

Figure 3 is a section on the line 3—3, Fig. 2; and

Fig. 4 is a perspective showing one section of the covering in place.

The pipe or other hot or cold fluid container 1, Fig. 1, may be provided, if desired, with any suitable or known inner covering 2, which may be a laminated or plastic magnesia or magnesia and asbestos split cylinder of standard lengths, having the transverse joints 3 and the longitudinal joints 4, Fig. 4. Although such coverings are effective as compared with the art which preceded them, they still inevitably leak a considerable stream of hot or cold air, as the case may be, through the joints 3 and 4, representing a continuous convection from the space between the covering 2 and the pipe 1 of lost heat. For thorough insulation it is desirable to supplement the

plastic or other covering 2 with a further coating having little or no conducting power and as impervious as practicable to the flow of heated or chilled air from the interstices of the covering 2 and the spaces between the sections of the cover 2 and the pipe 1.

The above purposes are effectively carried out by the provision of a layer of hair-felt or some other mat or bat of aggregated fibrous material containing air in its interstices, but difficulty has heretofore existed in applying such a layer of fibrous material. So far as I am aware, when previously formed sections of felt or fibrous material have heretofore been provided, it has been necessary to mount them upon a piece of paper or like carrier, which in use is exterior to the felt proper when it is curved about the pipe. With such arrangement much of the advantage of the fibrous covering is lost through inability to make a good fit between the edges of the fibrous coat either longitudinally of the pipe or transversely between the sections applied to the pipe, and through the discontinuity of the exterior coatings.

Referring now to Fig. 2, I prefer to prepare the cover sections in preformed sizes, each comprising a quadrilateral, preferably rectangular, waterproof paper, cloth or laminated sheet covering 10. Along one side of this sheet but extending less than its whole length an adhesive 11, such as glue, silicate of soda, or other cement, is spread to a transverse extent preferably of something less than one-fourth of the transverse dimensions of the sheet 10, and upon this a rectangular mat 12, of hair-felt, hair and asbestos, or asbestos or hair mixed with any preferred textile fiber, is then caused to adhere with its upper edge 13 preferably coincident with the upper edge of the sheet 10, and with one of its edges projecting as at 14 slightly beyond the subjacent edge of the sheet 10. The sheets 10 and 12 are joined together at the adhesion 11, but are free elsewhere, as shown in Fig. 3.

By this construction the sheet 10 overlaps the felt section 12 at a transverse margin 15 and at a longitudinal margin 16, and the mat 12 smoothly covers the pipe without wrinkling under transverse compression.

The vertical dimension of the sheet 12 as shown in Fig. 2 is sufficient for the circum-

ference of the surface to be covered, or for one-half of such surface, or any other even divisor of such surface. But this dimensional relation to the place where the covering is to be applied is not necessarily exact, since the covering 12 is compressible in any direction longitudinally or transversely of its general extent.

The sections 10-12 of the covering are applied as illustrated in Figs. 1 and 4; starting at the edge 13 which is placed longitudinally of the pipe, the mat 12 is first rolled around the pipe until its lower edge 17, Fig. 2, contacts with its upper edge 13. The edge 17 may be sheared away if there is too much material for a particular situation, but a wide variation of width can be taken care of by the smooth transverse compression of the free mat 12. The edge 18, if the sections are being installed from left to right, Fig. 1, is compressed against the projecting edge 14 of the last applied section, and the overlap 15 of the sheet 10 is then carried around outside of the last sheet 10, the edge 16 overlapping the part of the sheet 10 to which the mat 12 is fastened by the adhesive 11. If desired, the overlapped edge 16 may be fastened by a suitable adhesive, but the usual procedure is to apply metallic bands 20 of any desired construction to retain the cover sections in place.

It will be observed that wherever the edges of these mats 12 engage each other, the mats 12 are at this point compressed to close fitting relation. When in place the covering 12 is therefore texturally continuous, having no interstices through which the heated or chilled air surrounding the pipe 1 can escape more readily than at other places in said cover.

I claim:

1. An insulating covering section comprising a cover sheet and a fibrous mat conjoined at a place along a narrow longitudi-

nal area of said parts, the parts being free 45 of other attachment to each other, whereby to permit smooth wrapping on a cylindrical surface of both mat and cover.

2. An insulating covering section comprising a quadrilateral cover sheet and a quadrilateral fibrous mat conjoined at a place along a narrow longitudinal area of said parts, the parts being free of other attachment to each other, and the fibrous mat being smaller than the cover, whereby to overlap the mat at two adjacent edges thereof.

3. An insulating covering section comprising a quadrilateral waterproof cover sheet and a smaller quadrilateral fibrous mat cemented together near one edge only of the cover, the mat projecting beyond the cover at one edge, and the cover projecting beyond the mat at another edge.

4. An insulating covering section comprising a rectangular cover sheet and a smaller rectangular fibrous mat joined together, the fibrous mat overlapping one edge of the cover, and the cover overlapping two other edges of the fibrous mat, whereby the 70 mat can be rolled into cylindrical form with edges of adjacent sections in compressing contact and covered by one of the overlapping cover edges.

5. An insulating cover section comprising a rectangular waterproof fabric cover sheet and a smaller rectangular hair-felt mat joined together, the fibrous mat overlapping one edge of the cover, and the cover overlapping two other edges of the fibrous 80 mat, whereby the mat can be rolled into cylindrical form with meeting edges of the same and adjacent sections in compressing contact and each covered by one of the overlapping cover edges.

Signed by me at New York, N. Y., this 19 day of April, 1919.

JOHN S. CARROLL.
